UNITED STATES PATENT OFFICE.

FREDERICK D. STUART, OF DOUGLASTON, NEW YORK.

SPRING-WHEEL.

1,179,774.

Specification of Letters Patent. Patented Apr. 18, 1916.

Application filed September 10, 1915. Serial No. 50,030.

To all whom it may concern:

Be it known that I, FREDERICK D. STUART, a citizen of the United States of America, residing at Douglaston, in the county of 5 Queens and State of New York, have invented new and useful Improvements in Spring-Wheels, of which the following is a specification.

This invention relates to certain novel 10 and useful improvements in spring wheels.

In carrying out the present invention, it is my purpose to improve and simplify the general construction of spring wheels and to provide a wheel wherein the tire sur- 15 rounding the felly may move relatively to the latter so as to compensate for any inequality in the roadway, and wherein the parts will be so correlated and arranged as to reduce the possibility of derangement to 20 a minimum.

It is also my purpose to provide a spring wheel which may be manufactured and marketed at small cost, which will be strong and durable in construction and which will 25 operate efficiently and effectively for its intended purpose.

With the above and other objects in view, the invention consists in the construction, combination and arrangement of parts 30 hereinafter set forth in and falling within the scope of the claim.

In the accompanying drawing; Figure 1 is a fragmentary side elevation of a spring wheel constructed in accordance with the 35 present invention. Fig. 2 is a cross sectional view therethrough.

Referring now to the drawing in detail, 1 designates the felly of the wheel. Secured to the side edges of the felly 1 and 40 projecting outwardly therefrom are annular plates 2, 2 and secured to the inner surfaces of the plates 2, 2 adjacent to the peripheries thereof and projecting inwardly toward each other are rings 3, 3.

45 4 designates an annulus U-shape in cross section and disposed between the rings 3, 3. The inner ends of the limbs of the annulus 4 are bent outwardly at right angles to themselves as at 5 and the right angular 50 portions 5 of the limbs lie within the respective rings 3 concentrically of the latter and are spaced apart therefrom as clearly illustrated in Fig. 2. Interposed between the confronting surfaces of the rings 3 and

right angular portions 5 of the annulus 4 55 are supporting springs 6 of the retractile type and each spring has one end secured to the particular ring 3 and the opposite end fastened to the corresponding flange 5. These springs 6 are spaced apart equi- 60 distant about the wheel and act to hold the annulus 4 yieldingly connected with the rings 3 on the side plates 2 so that such annulus may move relatively to the side plates within the latter when occasion demands. 65

Surrounding the annulus 4 and riveted or otherwise connected to the central member thereof is a spring wheel band 7 and surrounding the band 7 and suitably secured thereto is a solid rubber tire 8. Interposed 70 between the confronting faces of the tire 8 and the band 7 is a strip of leather 9 or similar material and the side plates of the leather strip 9 overlie the similar edges of the spring wheel band 7 and are secured to 75 the outer surfaces of the side plates 2 by bolts 10 or other appropriate fastening devices. The outer edges of the leather strip 9 are slack as is illustrated in Fig. 2 so that the rubber tire 8, spring wheel band 7 and 80 supporting annulus 4 may move freely relatively to the side plates 2 and the felly 1. Interposed between the outer surface of the felly and the central member of the annulus 4 are coiled expansion springs 11 spaced 85 apart about the felly equal distances and co-operating with the springs 6 to maintain the annulus 4, band 7 and rubber tire 8 in normal position. Coiled retractile springs 10' are arranged about the felly 1 between 90 the felly and the flanges 5 on the U-shaped annulus 4 and the inner ends of these springs are secured to the felly, while the outer ends thereof are connected to the flanges 5, as clearly illustrated in Fig. 1 of 95 the drawing, and these springs 10' counteract the spring 6.

In practice, when an obstruction is encountered in the road the adjacent portion of the tire 8 and band 7 move toward the 100 felly 1 and in this movement of the rubber tire and the band 7 the lower portion of the annulus 4 moves into the spaces between the side plates 2 while the portion of such annulus moves out of the space between the side plates. In this movement of the annulus the action of the springs 6 and 11 is 105 counteracted so that when the tire is re-

lieved of the influence of the obstruction the springs react to restore the parts to normal position.

I claim:

- 5 In spring wheel construction, a felly, side plates secured to the opposite edges of the felly and projecting outwardly therefrom, rings secured to the inner surfaces of said side plates adjacent to the peripheries thereof and projecting inwardly toward each other, an annulus U-shaped in cross section disposed between the said rings and having the inner edges of the limbs thereof bent outwardly at right angles to themselves and disposed concentrically of the respective rings, retractile springs interposed between said rings and right angular portion of said annulus and each having one end secured to the particular ring and the opposite end fastened to the corresponding flange and acting to hold the annulus in normal position, a rubber tire surrounding
- 10
- 15
- 20

the central member of said annulus concentrically of the latter and secured thereto, a spring wheel band interposed between said tire and the adjacent portion of said annulus, a strip of leather disposed between the confronting faces of said rubber tire and said spring wheel band and having the edges thereof secured to the respective side plates and slack, expansion springs interposed between said felly and the central member of said annulus and spaced apart equal distances about the felly and coöperating with the first-mentioned springs to hold the annulus in proper position, and springs connecting the flanges on said U-shaped annulus to said felly and counteracting the first-mentioned springs.

FREDERICK D. STUART.
